UNITED STATES PATENT OFFICE.

DALLAS A. BODIKER AND BERT FIALA, OF DAYTON, OHIO.

SHIELD FOR BOX-OFFICE WINDOWS.

Application filed November 25, 1921. Serial No. 517,707.

This invention relates to a shield for box office windows and the like.

Ticket selling offices, booths, and the like are usually provided with a front wall of glass and have in that wall a relatively small opening through which the tickets and money may be passed, or other business transacted. It is desirable that means be provided for normally closing this opening, first, because in cold weather it is very difficult to properly heat the booth, or office, if the opening is not closed, and, second, because when the opening is not closed it is possible for a person on the outside of the office to reach through the same and secure money or other articles of value resting upon the counter, or shelf, inside the opening.

The object of the present invention is to provide a shield for closing the opening in a window of this kind which will have means for retaining the closure normally in a closed position and for automatically opening the same when released.

A further object of the invention is to provide such a device which will be independent of the construction of the wall, or booth, to which it is applied, and may, therefore, be affixed to the window as an attachment.

A further object of the invention is to provide such a device which will be simple in its construction and operation and which will be produced at a relatively low cost.

Other objects of the invention will appear as the device is described in detail.

In the accompanying drawings Fig. 1 is a front elevation of the window of a ticket booth showing our invention applied thereto; Fig. 2 is a rear elevation of the shield; Fig. 3 is a plan view of the shield; Fig. 4 is a section taken on the line 4-4 of Fig. 3, showing the latch; Fig. 5 is a section taken on the line 5-5 of Fig. 2; and Fig. 6 is an edge view of the shield showing the releasing lever.

In these drawings we have illustrated one embodiment of our invention and have shown the same as applied to the window of a ticket seller's booth, such as is commonly employed in motion picture theaters and the like, but it will be understood that not only may the invention be used with offices or booths of various kinds but that the shield itself may take various forms and may be controlled in various ways without departing from the spirit of the invention.

In Fig. 1 of the drawings we have shown the booth as having the usual front wall of glass, 1, which extends upwardly from a counter or shelf and which is provided in its lower portion with an opening 2 through which tickets may be passed, or other business transacted and which is preferably formed in the lower edge of the glass wall directly above the counter. These openings are of various sizes and may be of any suitable shape, but are usually semi-circular in shape. The shield is constructed independently of the booth and is adapted to be applied thereto with its closure in line with the opening 2. To this end the shield preferably comprises a supporting frame adapted to be secured to the booth or office structure within the front wall 1 and close to, or in engagement with, that wall. The frame is provided with an opening in line with the opening 2. The openings in the frame and in the front wall may be of the same size and shape, but this is not necessary as where a booth is provided with an opening larger than necessary the frame may have a small opening and may be of such width that it will overlap the edges of the opening in the front wall of the booth, thus reducing the size of the opening in the front wall. Movably mounted upon the frame is a closure of a size and shape to close the opening in the frame, and this closure is held normally in its closed position but is preferably provided with means for automatically moving it into its open position when it is released. As has been stated, the frame and closure may be of various shapes and in the present construction we have shown the shield as comprising a semi-circular frame 3 of such a width that when the ends thereof rest upon the shelf, or counter, at the bottom of the window 1, the frame will overlap the edge of the wall about the opening 2. The frame may be secured in position in any suitable manner, but, as here shown, it is provided at each end with an apertured base plate, 4 and 5, through which screws may be inserted to secure it to the shelf, or counter, thus enabling the frame to be close to, or in contact with, the glass wall of the booth and secured in that position. The closure is, in the present instance, also substantially semi-circular in shape, as shown at 6, and is pivoted at one end upon the frame 3. To this end the frame is provided with upwardly extending lugs 7 between

which the end of the closure 6 extends, as shown in Fig. 5, and between which it is mounted on a pivot pin 8, mounted in a boss, or bearing, 9 formed integral with one of the lugs 7. The closure is preferably acted upon by a spring which will move it into its open position when it is unrestrained and in the present instance we have rigidly secured the closure to the pivot pin 8, and 10 journaled the pivot pin in the bearing 9 and have coiled a spring 10 about the pivot pin with one end connected therewith. The other end of the spring may be connected with the bearing in any suitable manner. 15 As here shown a bushing 11 is inserted in the bearing about the pivot pin and the one end of the spring connected with this bushing. By rotating the bushing within the bearing and securing it in its adjusted positions by means of a set screw 12, the tension on the spring may be regulated. A stop 13 arranged between the upper portions of the lugs 7 limits the movement of the closure by the spring. 20

25 The means for retaining the closure in its closed position is preferably located at that end thereof opposite the pivot 8 and, as here shown, this means comprises a latch 14 pivotally mounted between lugs 15 at that end of the frame 3 opposite the lugs 7. These lugs are spaced apart to permit the end of the closure to enter the space between them and the closure is provided with a stop, such as a shoulder 16, to be engaged by 30 the latch 14. The latch is acted upon by a spring 17 which holds it yieldably in a position to engage the shoulder 16 on the closure, and thus normally lock the latter in its closed position. It will be noted that the shoulder 16 and the nose of the latch are beveled so that the nose of the latch may be moved downwardly out of engagement with the shoulder to release the closure. The direction of movement of the shoulder when the closure is moved toward its open position, is such that the spring 10 cannot force the shoulder out of engagement with the latch. Rigidly secured to the latch is a 35 finger 18 by means of which the latch may be actuated to move it into an inoperative position with relation to the closure, this being preferably accomplished by means of a tripping lever 19 pivotally mounted on the base plate 4 and engaging the finger 18. It 40 will be apparent, therefore, that by merely depressing the lever 19 the closure may be released and automatically opened, the tripping finger being arranged adjacent to the counter in a position in which it may quickly and easily engaged by the finger of the operator. The closure 6 is preferably provided 45 on its inner side with a finger piece, such as a knob 20, by means of which it may be restored to its closed position by means of this construction of the window closure the latter

may be installed without mutilating the counter and may be operated without in any way interfering with anything resting upon the counter.

The operation of the device will be readily understood from the foregoing description and it will be apparent that the opening 2 will be normally closed by the closure 6, the closure being locked so as not only to exclude the cold air and wind but to prevent any access being had to the interior of the booth through the opening. When a customer approaches the booth it is only necessary for the ticket seller to depress the trip lever 19 and the closure 6 will be automatically moved out of line with the opening, thus permitting the tickets to be sold or other business to be transacted. This releasing operation is very easily performed and will not in any way interfere with the other 50 duties of the ticket seller. After the transaction has been completed the closure is restored to its normal position in which position it is automatically locked by the latch 14. 55

While we have shown and described one embodiment of our invention we wish it to be understood that we do not desire to be limited to the details thereof as various modifications may occur to a person skilled 60 in the art.

Having now fully described our invention what we claim as new and desire to secure by Letters Patent, is:

1. The combination with a counter, a wall 100 extending upwardly therefrom and having an opening adjacent to said counter, of a frame having an opening therein, adapted to be mounted on said counter on one side of said wall with said opening in line with the opening in said wall and with the edge of said frame overlapping the edge of said wall about the opening therein, a closure mounted on said frame for movement in a plane substantially parallel with said frame, and means for securing said closure normally in its closed position.

2. The combination with a counter, a wall 105 extending upwardly therefrom and having an opening adjacent to said counter, of a frame having an opening therein, adapted to be mounted on said counter on one side of said wall with said opening in line with the opening in said wall, and with the edge of said frame overlapping the edge of said wall 110 about the opening therein, a closure mounted on said frame for movement in a plane substantially parallel with said frame, means for securing said closure normally in its closed position, and means for automatically 115 moving said closure to its open position when released from said securing means.

3. The combination with a counter, a wall 120 extending upwardly therefrom and having an opening adjacent to said counter, a frame 125

having an opening therein and mounted on said counter on one side of said wall with said opening in line with the opening in said wall, a closure pivotally mounted on said frame on an axis extending transversely thereto for movement into and out of line with said openings, a spring acting on said closure to move it toward its open position, and a latch to retain said closure in its closed position.

4. The combination with a counter, a wall extending upwardly therefrom and having an opening adjacent to said counter, a frame having an opening therein and mounted on said counter on one side of said wall with said opening in line with the opening in said wall, a closure pivotally mounted on said frame on an axis extending transversely thereto at one side of said opening and movable into and out of line with said opening, a latch arranged at the other side of said opening to engage said closure and retain the same in its closed position, and a spring acting on said closure to move the same into its open position when released from said latch.

5. A self-contained shield of the character described comprising a frame having means for securing the same in a fixed position adjacent to and substantially parallel with a wall having an opening therein, said frame having an opening to register with the opening in said wall, a closure mounted on said frame for movement into and out of line with the opening therein, a spring carried by said frame and acting on said closure to move the same to its open position, and a latch mounted on said frame and arranged to automatically engage said closure when the latter is moved to its closed position and to retain said closure in its closed position.

6. A self-contained shield of the character described comprising a frame having means for securing the same in a fixed position adjacent to and substantially parallel with a wall having an opening therein, said frame having an opening to register with the opening in said wall, a closure pivotally mounted on said frame at one side of said opening for movement in a plane substantially parallel with said frame, a spring carried by said frame and acting on said closure to move the same to its open position, and a latch mounted on said frame at the other side of said opening and arranged to automatically engage said closure when the latter is moved to its closed position and retain said closure in its closed position.

7. A self-contained shield of the character described comprising a frame having means for securing the same in a fixed position adjacent to and substantially parallel with a wall having an opening therein, said frame having an opening to register with the open-

ing in said wall, a closure pivotally mounted on said frame at one side of said opening for movement in a plane substantially parallel with said frame, a spring carried by said frame and acting on said closure to move the same to its open position, a latch mounted on said frame at the other side of said opening and arranged to automatically engage said closure when the latter is moved to its closed position and retain said closure in its closed position, and a device carried by said frame and acting on said latch to move the same into an inoperative position and thereby release said closure for movement by said spring.

8. A device of the character described, comprising a frame having an opening therein and having at each side of said opening a pair of spaced lugs, a closure having one end arranged between the lugs of one pair, a pivot pin mounted in one of said lugs and supporting said closure, a spring acting on said pivot pin to move said closure into its open position, a latch mounted between the lugs of the other pair and arranged to engage said closure when it is moved to its closed position, and means for controlling the movement of said latch.

9. A device of the character described, comprising a frame having an opening therein and having at each side of said opening a pair of spaced lugs, a closure having one end arranged between the lugs of one pair, a pivot pin mounted in one of said lugs and supporting said closure, a spring coiled about said pivot pin and acting thereon to move said closure into its open position, means for regulating the tension of said spring, a latch arranged between the lugs of the other pair and adapted to engage said closure when it is moved into its closed position, and means for controlling the movement of said latch.

10. In a device of the character described, a substantially semi-circular frame having at each end thereof means for securing it to a supporting structure, a closure pivotally mounted at one end of said frame and movable into a position in line therewith, a spring carried by said frame and acting on said closure to move the same into an elevated position, a latch pivotally mounted at the opposite end of said frame and arranged to engage said closure when it is moved into line with said frame and retain the same in that position, a spring acting on said latch to hold it normally in its operative position, and a hand lever mounted on said frame and arranged to actuate said latch to release said closure.

11. The combination with a counter and a wall extending upwardly therefrom and having an opening therethrough adjacent to said counter, of a closure pivotally mounted for movement in a plane substantially par-

allel with and adjacent to said wall, means for securing said closure normally in its closed position, and means for automatically moving said closure to its open position when released from said securing means.

12. The combination with a counter and a wall extending upwardly therefrom and having an opening therethrough adjacent to said counter, of a closure pivotally mounted for movement in a plane substantially

parallel with and adjacent to said wall, a spring acting on said closure to move it to its open position, a latch arranged to automatically engage said closure and maintain the same in its closed position, and means to 15 actuate said latch to release said closure.

In testimony whereof, we affix our signatures hereto.

DALLAS A. BODIKER.
BERT FIALA.
